UNITED STATES PATENT OFFICE.

RALPH P. TUTTLE, OF NEW YORK, N. Y., AND MATTHEW H. LOUGHRISE, OF WOODCLIFFE-ON-HUDSON, NEW JERSEY.

SEMAPHORE SIGNAL DEVICE.

1,242,891.

Specification of Letters Patent.

Patented Oct. 9, 1917.

Application filed September 30, 1913. Serial No. 792,624.

To all whom it may concern:

Be it known that we, RALPH P. TUTTLE, a citizen of the United States, residing in the borough of Richmond, city, county, and State of New York, and MATTHEW H. LOUGHRISE, a citizen of the United States, residing at 313 31st street, Woodcliff-on-Hudson, county of Hudson, and State of New Jersey, have invented certain new and useful Improvements in Semaphore Signal Devices, of which the following is a specification.

Our invention relates to signal devices, and particularly to semaphore signal devices used in connection with railway signal mechanisms. The objects of our invention are to provide means for reinforcing a light metallic blade and a means of supporting this blade from its operating member in such a way as to present an unbroken surface from one side. Further objects of our invention are to provide a means for supporting a light enameled blade at frequent intervals on a line near its longitudinal axis, in this way distributing its weight and rendering the enamel less liable to crack at the points of support.

We attain these objects by the construction illustrated in the accompanying drawings forming a part of this specification, in which Figure 1 is a front view of a semaphore signal device embodying our invention with the blade partly broken away to show the method of fastening. Fig. 2 is an enlarged cross-section on line $x-y$ of Fig. 1. Fig. 3 is a rear view (in perspective) of the signal blade and its supporting member shown in Fig. 1.

Similar characters of reference designate corresponding parts in all the illustrations.

A, designates what is termed in the art as a spectacle casting carrying colored glass disks, a^1 , a^2 , and a^3 . This casting as usual is mounted on a shaft 1 which is operated to move the casting and with it the colored glasses and blade B, against the usual bias of the casting and blade. The form of invention shown in the drawings is adapted for use in connection with semaphore signal devices of the kind giving indications in the upper quadrant. The invention is, however, equally applicable to devices giving indications in the lower quadrant and to center pivoted devices giving the indication par-

tially in the lower and partially in the upper quadrant. 55

B designates a blade secured to the casting A through a supporting member C which is fastened to A at its blade grip 2. The blade is made of light gage sheet metal 60 and preferably enameled with a glaze enamel which preserves the metal and provides a fast color. The supporting member C is designed to reinforce the blade B and to support it at frequent intervals near its longitudinal axis also to form a method of attachment to the casting A which falls behind the plane of the blade and is entirely concealed thereby. This support (see Fig. 3) has a relatively long tapering arm 11 70 with a V shaped tapering rib 12 to secure maximum stiffness with a minimum of weight and horizontal surface for the retention of snow and ice. This arm extends along the longitudinal axis at the back of the blade 75 which is secured to it by means of suitable rivets 6. Toward the blade grip this support flares outwardly and is offset at 13 as shown in Fig. 2 having parallel edges 14 turned up to face the blade grip 2. These 80 edges are provided with slots 5^a , 5^b , 5^c and 5^d by means of which bolts 4^a , 4^b &c., secure the blade support and the casting A together. The object of slotting the holes is to facilitate attaching the blade to the spectacle casting. Owing to the small clearance below the blade for the bolt head, the bolts could only be inserted with difficulty, if at all, if holes were provided in the support instead 85 of slots. Another advantage obtains in practice from slotting these holes, as this enables the two lower bolts to be inserted in the spectacle casting and the blade afterward slipped into place; these bolts forming a support for it until the other bolts are inserted. 90

As shown in Fig. 3 the off-sets 13 also have extensions 13^a , 13^b and the parallel edges 14 have extensions 14^a , 14^b which are turned inward as shown inclosing the space 100 between the blade grip and the blade to the exclusion of snow and ice. In some cases the blade B has a stiffening rib rolled on the edges as b.

In the illustrations described a light sheet 105 metal blade is shown supported by a comparatively heavy supporting piece to which it is rigidly attached.

With this arrangement it is possible to construct a very strong blade of very light sheet metal and concentrate the main part of the weight at a point near the pivot also the supporting member is entirely concealed from the front.

Having thus described our invention, what we claim is:

1. In a railway signal device, the combination of a semaphore casting, a comparatively light gage sheet metal blade, a comparatively heavy gage member secured to, but of less area than said blade and having an offset portion, means for attaching said offset portion to said semaphore casting whereby the attaching means are concealed from view on one side of the blade.
2. In a semaphore signal device the combination of an intermediate reinforcing member secured to an enameled semaphore member, said reinforcing member being secured to, and wholly supporting, said semaphore member, and said reinforcing member being concealed from the front of the blade.
3. In combination, a semaphore casting, a sheet metal blade, a one piece tapering reinforcing member secured to the back of said blade and attached to said semaphore casting, said reinforcing member being expanded laterally at the point of attachment to said semaphore casting.
4. In a railway signal device, a spectacle, a blade, a reinforcing member comprising an arm extending along the longitudinal axis of the blade and secured thereto and offset members at one end of the arm, which

offset members serve as an exclusive means for the attachment of the blade to said spectacle.

5. In a railway signal device, a spectacle, a blade, a reinforcing member comprising an arm extending along the longitudinal axis of the blade and secured thereto and offset members at one end of the arm which are slotted at their edges, which slotted offset members serve as a means for the attachment of the blade to said spectacle.

6. In a railway signal device, a spectacle, a blade, a reinforcing member comprising an arm tapering longitudinally and extending along the longitudinal axis of the blade and secured thereto and offset members at one end of the arm, which offset members serve as an exclusive means for the attachment of the blade to said spectacle.

7. In a railway signal device, a spectacle, a blade, a reinforcing member comprising a V shaped arm in cross-section and extending along the longitudinal axis of the blade and secured thereto and offset members at one end of the arm, which offset members serve as an exclusive means for the attachment of the blade to said spectacle.

In witness whereof, we have hereunto subscribed our signatures in the presence of two witnesses.

RALPH P. TUTTLE.
MATTHEW H. LOUGHRIIDGE.
